CLAIM

The ornamental design for water chiller for ice bath, as shown and described.

DESCRIPTION

FIG. 1 is a front perspective view of the water chiller for ice bath, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged detail view of area 9 in FIG. 1;

FIG. 10 is an enlarged detail view of area 10 in FIG. 1;

FIG. 11 is an enlarged detail view of area 11 in FIG. 1;

FIG. 12 is an enlarged detail view of area 12 in FIG. 1;

FIG. 13 is an enlarged detail view of area 13 in FIG. 1; and,

FIG. 14 is an enlarged detail view of area 14 in FIG. 2.

The broken lines in the drawings illustrate the portions of the water chiller for ice bath, which form no part of the claimed design.

The dash-dot-dash broken lines in FIGS. 1, 2, 9, 10, 11, 12, 13 and 14 show the boundaries of the enlargements shown in FIGS. 9, 10, 11, 12, 13 and 14, and form no part of the claimed design.

1 Claim, 14 Drawing Sheets
